FLAT SHEET DELIVERY FOR WEB PRINTING
ROTARY PRESSES

Howard M. Barber, Pawcatuck, Conn., assignor
to C. B. Cottrell & Sons Company, Westerly,
R. I., a corporation of Delaware

Application May 20, 1936, Serial No. 80,667

6 Claims. (Cl. 271—79)

The object of my invention is to provide means for severing sheets from a printed web, means for advancing the web through the cutters and means for delivering the sheets cut from the web.

5 My invention comprises, generally, means for depressing the tail end of a sheet cut from the web and then retarding the sheet for delivering it, without disturbing the travel of the web.

My invention more specifically comprises upper 10 and lower coacting rotary and oscillating nippers, the upper rotary nipper serving in its movement to first depress the tail end of a sheet into contact with the lower oscillating nipper and then to move rapidly out of the path of the oncoming 15 web; the lower nipper serving to act as a drag for retarding the sheet to permit it to fall upon the pile with slight momentum.

A practical embodiment of my invention is represented in the accompanying drawings, in 20 which

Fig. 1 represents a diagrammatic side view of a web printing rotary press with my improved flat sheet delivery applied thereto; and

Fig. 2 represents an enlarged detail side elevation 25 of the delivery.

The printing unit is shown as comprising an impression cylinder 1 and its coacting form cylinders 2, 3, 4, 5. The traveling web is denoted by 6 and the sheets cut therefrom by 7, which sheets 30 go to make up the flat sheet delivery pile 8. The web travels around the rolls 9 and 10 on its way to and from the printing unit.

The horizontally disposed endless carrier 11 is shown as of the well known side chain type and 35 it is provided with pairs of side grippers 12 spaced apart and arranged to be operated in the usual manner by the cams 13 for grasping the web as it leaves the printing unit and forward the web between coacting rotary cutters 14, 15 40 where the sheets 7 are severed from the web. It will be understood that these side grippers 12 retain their engagement with the leading ends of the sheets 7 until time to deliver them, when the grippers 12 are opened by the usual cams 45 16 for releasing the sheets.

Means are provided for depressing the tail ends of the sheets 7 as they approach the sheet delivery pile 8 and for retarding the sheets to permit their proper deposit flat upon the pile, which 50 means is constructed, arranged and operated as follows:

Upper and lower coacting rotary and oscillating nippers are employed. The rotary upper nipper comprises a cross shaft 17 having fixed 55 thereto a crank arm 18. A two armed spring

pressed adjustable nipper roller lever is pivoted on the crank arm 18, the arm 19 of which lever carries the nipper roller 20 and the arm 21 of which lever carries an adjusting screw 22 bearing against the nipper crank arm 18 for adjusting the normal position of the nipper roller 20. A spring 23 is interposed between the crank arm 18 and the nipper lever arm 19 for urging the roller 20 outwardly.

The oscillating lower nipper comprises a cross 10 shaft 24 which carries an uprising nipper arm 25 fast thereon and having an extended sheet contacting surface 26 for coaction with the roller 20 of the rotary upper nipper. This lower nipper arm 25 is oscillated from the upper nipper cross 15 shaft 17 through the crank disc 27, connecting rod 28 and rock arm 29, which rock arm is loosely mounted on the cross shaft 24 and is connected through an adjusting device including a screw 30 with an arm 31 fixed on the cross shaft 24 20 and thereby fixedly connected to the lower nipper arm 25; for adjusting the position of the said lower nipper with respect to the upper nipper. The screw 30 is rotatably supported on the arm 31 and threadedly engages a lug on the rock 25 arm 29. The upper nipper is rotated once and the lower nipper is oscillated once, for every length of sheet as follows:

A sprocket wheel 32 which is mounted on a cross shaft 33 is driven by one of the side chains 30 of the endless carrier 11, which cross shaft has a gear 34 meshing with a gear 35 on the cross shaft 36. An elliptical gear 37 on the cross shaft 36 drives an elliptical gear 38 on the upper nipper cross shaft 17. This train of gears not only 35 permits the upper nipper to be rotated once for every length of sheet and the lower nipper oscillated once for every length of sheet but it also varies the movement of the said nippers. This variation in the circular movement of the upper 40 nipper 20 permits the upper nipper to be speeded up and slowed down during its rotation so that the nipper roller 20 may be caused to travel faster in its circular path at the time it is depressing the sheet into contact with the lower 45 nipper and when it is leaving the sheet, thus keeping the upper nipper roller 20 out of the way of the leading edge of the advancing web.

The grippers 12 on the endless carrier are caused to travel at the surface speed of the printing unit, as, for instance, by operatively connecting the impression cylinder gear 39 through the gears 40, 41 with the gear 42 on the inner cross shaft 43 of the endless carrier 11.

In operation, the relative positions of the up- 55

per and lower nippers should first be adjusted to correspond with the length of sheet to be handled. The printed web 6 as it leaves the roll 10 of the printing unit is engaged by a pair of side grippers 12 on the endless carrier 11 and advanced through the coacting rotary cutters 14, 15. After a sufficient length of the web has passed through the cutters the sheet is severed from the web, the grippers 12 retaining their 10 grasp on the side edges of the leading end of the sheet until time for releasing the sheet to deliver the same. As the tail end of the sheet reaches a point between the upper and lower nippers the roller 20 of the upper nipper which is moved 15 downwardly and outwardly at an increased speed will come into contact with the upper face of the sheet at its tail end and depress it into contact with the surface 26 of the outwardly moving lower nipper as the grippers 12 release the 20 leading end of the sheet. The roller 20 then rolls off the sheet and moves forwardly and upwardly at a surface speed sufficient to keep it out of the way of the advancing web. The lower nipper because of its slower oscillating movement will 25 retard the sheet and finally permit the sheet to drop upon the pile as the lower nipper moves rearwardly to complete its oscillating movement. It is evident that various changes may be resorted to in the construction, form and arrangement of the several parts without departing from the spirit and scope of my invention, and hence I do not intend to be limited to the particular embodiment herein shown and described, but what I claim is:

30 1. In a sheet delivery mechanism for printing presses, means for advancing the sheets, means for releasing the sheets at their delivery point, coacting rotary and oscillating nippers for depressing the tail ends of the sheets and thereafter positively retarding the sheets as they are released, and means for varying the speed of movement of the nippers.

35 2. In a sheet delivery mechanism for printing presses, means for advancing the sheets, means for releasing the sheets at their delivery point, coacting rotary and oscillating nippers for depressing the tail ends of the sheets and thereafter positively retarding the sheets as they are released, and means for causing the rotary nippers to complete one revolution for each sheet 40 and for speeding the nippers up as they ap-

proach, depress and leave the tail end of the sheet.

3. In a sheet delivery mechanism for printing presses, an endless carrier, means thereon for advancing the sheets, means for releasing the sheets at their delivery point, and means for depressing the tail ends of the sheets and thereafter positively retarding the sheets as they are released, said means comprising an oscillating lower nipper, a rotary upper nipper coacting therewith and 10 mechanism for imparting a variable speed to the nippers.

4. In a sheet delivery mechanism for printing presses, an endless carrier, means thereon for advancing the sheets, means for releasing the sheets at their delivery point, and means for depressing the tail ends of the sheets and thereafter positively retarding the sheets as they are released, said means comprising an oscillating lower nipper, a rotary upper nipper having a 15 spring pressed roller coacting with the lower nipper and mechanism for imparting a variable speed to the nippers.

5. In a sheet delivery mechanism for printing presses, an endless carrier, grippers thereon for advancing the sheets, means operating on the grippers for releasing the sheets at their delivery point, and means for depressing the tail ends of the sheets and thereafter positively retarding the sheets as they are released from the carrier grippers, said means comprising an oscillating lower nipper and a rotary upper nipper having a 20 spring pressed roller coacting with the lower nipper and means for adjusting the position of the said oscillating lower nipper with respect to the upper 30 nipper.

6. In a sheet delivery mechanism for printing presses, an endless carrier, grippers thereon for advancing the sheets, means operating on the grippers for releasing the sheets at their delivery point, and means for depressing the tail ends of the sheets and thereafter positively retarding the sheets as they are released from the carrier grippers, said means comprising an oscillating lower nipper and a rotary upper nipper 40 having a spring pressed roller coacting with the lower nipper and means for adjusting the normal position of the said rotary upper nipper and separate means for adjusting the position of the said oscillating lower nipper with respect 45 to the upper nipper.

HOWARD M. BARBER.
